UNITED STATES PATENT OFFICE.

ALBERT ABBATICCHIO, OF LATROBE, PENNSYLVANIA.

DESIGN FOR A FRAMED PICTURE.

No. 39,681.

Specification for Design.

Patented Dec. 8, 1908.

Application filed March 18, 1907. Serial No. 363,155. Term of patent 7 years.

To all whom it may concern:

Be it known that I, ALBERT ABBATICCHIO, residing at Latrobe, in the county of Westmoreland and State of Pennsylvania, United States of America, have invented a new, original, and ornamental Design for Framed Pictures, of which the following is a specification, reference being had to the accompanying drawing, forming part thereof.

The figure is a face view of a framed picture showing my new design, which consists of an approximately rectangular frame wherein is inclosed the representation of a dog; and a chain leading from a representation of a collar surrounding the dog's neck and held at its other end to the frame by a pad-lock.

I claim

The ornamental design for a framed picture, as shown and described.

ALBERT ABBATICCHIO.
